NECKTIE KNOT FORM

Hilmer E. Hanson, Chicago, Ill.

Application June 28, 1947, Serial No. 757,842

2 Claims. (Cl. 2—153)

1

The invention relates to an article or element adapted for use in the tying of a necktie and has for its principal object the provision of an improved inexpensive knot form by means of which a neat and attractive knot may be tied in the ordinary four-in-hand necktie without resorting to any complicated tying procedures. Other objects of the invention are to provide a knot form that includes portions by means of which the form may be easily attached to a portion of the necktie so that it need not be held in place by hand while the knot is being tied; to provide an element or form tapered longitudinally and generally arcuate in transverse cross section so as to conform to the general shape of the conventional four-in-hand knot; to provide a form that will be completely concealed within the finished knot; and to provide an article of the class described that will not perforate, tear or otherwise damage the neckties with which it is used.

The foregoing and other important objects and desirable features of the invention will become apparent as the disclosure is more fully made in the following detailed description of a preferred embodiment of the invention as shown in the accompanying sheet of drawings in which:

Fig. 1 is a perspective view of the knot form *per se*;

Fig. 2 is a longitudinal section taken substantially on the line 2—2 of Fig. 1;

Fig. 3 is a transverse section taken substantially on the line 3—3 of Fig. 1; and

Figs. 4 to 8 are views of consecutive steps in the use of the form in conjunction with the tying of a knot in an ordinary four-in-hand necktie.

Reference in the following description to particular types of material of which the article may be formed and certain sizes that the article may assume, are, like other descriptive details, for the purpose of illustration only and should not be taken as limiting the application of the principles of the invention.

The knot form comprises essentially a member of relatively stiff though somewhat flexible material, and may be of metal, plastic, pressboard, impregnated fabric or other suitable material. The member is provided with an upper end portion 10 and a lower end portion 11 and is substantially arcuate in transverse cross section (Fig. 3) being generally triangular in shape and including a central body portion 12, the opposite sides which converge or taper from top to bottom as at 13. Stated otherwise, the member is substantially concavo-convex in its trans-

verse dimension, with the convex surface providing the front of the member and the concave surface providing the rear of the member, in such manner that the central body portion 12 is flanked at opposite sides by wings 14. Each wing inclines rearwardly and laterally outwardly from the proximate side edge 13 of the body 12 generally at an obtuse angle to the front surface of the body 12 (Fig. 3). The member is non-tubular in cross section; that is to say, the wings 14 terminate a short distance rearwardly of the rear surface of the body portion 12 without curving back upon the body and each wing includes a terminal edge 15 (Figs. 1 and 3) spaced laterally outwardly from the proximate side edge portion 13. The terminal side edges 15 of the wings 14 are generally parallel to their proximate side edges 13 and each wing is provided at its upper outer portion with a rounded corner 16 (Fig. 1) which blends into the upper or top end portion 10 of the member.

The member includes a hook or tongue element 17 integral with or otherwise joined to the upper end portion 10 of the member. A root portion of this hook or tongue element extends immediately rearwardly of the body portion 12 as shown in Fig. 3 and a torque portion of such element extends downwardly alongside the rear surface of the body a substantial distance toward the lower end portion 11. In Fig. 2 it can be seen that the hook element lies substantially in the cavity formed between the rearwardly curved wings and the central body of the device. The formation of the hook or tongue 17 in its relationship to the body 12 is preferably such that a slight degree of resiliency is imparted to the tongue so that it may have relative movement toward and away from the rear surface of the body 12, whereupon to effect a clamping or gripping action on the portion of a necktie 18 that may be introduced between the tongue 17 and body portion 12 (Fig. 4). The lower portion of the hook or tongue 17 is curved outwardly at 19 (Fig. 2) to facilitate the introduction of the necktie 18. When the member is attached to the necktie, it is hooked over a portion of the necktie in a direction normal to the principal axis of the tie and the relationship between the body 12 and hook or tongue 17 is such as to hold the member in place on the tie. In Figs. 2 and 3 it can be seen that the terminal edges 15 of the wings 14 project rearwardly from the rear face of the body 12 more distantly than the hook 10—17—19. Thus the wings 14 embrace a space wherein the hook is disposed. In Fig. 3 it is ap-

2

parent that the terminal edges of the wings 14 are spaced apart more distantly than the width of the hook 10—17—19 to provide a tie-receiving space between the hook and each of the wings 14. When so disposed within the tie-receiving spaces between said hook and the wing terminal edges 15 the tie will be bent into a serpentine formation illustrated diagrammatically by the dot dash line 18 in Fig. 3.

The member, as viewed in Fig. 2, is formed generally as an inverted U, the legs of which are represented by the wide arcuate body 12 and the flat and narrow tongue 17, these legs being substantially coextensive to the extent that the tongue 17 overlies a substantial portion of the body 12. The rearward and lateral curving or inclining of the wings 14 is such as to dispose the terminal side edges 15 of the wings rearwardly of the tongue 17. In other words, a chord across the generally arcuate cross section of the member passing through the terminal side edges 15 of the wings 14 will lie rearwardly of the tongue 17, whereupon the tongue 17 will be inside a plane including the terminal side edges 15, so that the necktie 18 may be introduced between the tongue 17 and body 12 and may further curve over the wings 14, as represented by the single dot-dash line in Fig. 3. This relationship of the components provides for the ability of the member to stay in place on the tie while the knot is being formed.

For the purposes of clarity in the description of the use of the knot-forming member, the necktie will be referred to as having a neckband portion N, a long end portion L and a short end portion S.

The first step in the use of the member is illustrated in Fig. 4, where it is shown that the member is attached to the long end of the tie closely adjacent the neckband portion N. In this respect the relative lengths of the portions S and L are the same as those usually adopted in the tie of the ordinary four-in-hand knot, the portion L being somewhat longer than the portion S. The portion L is then brought across or over the portion S adjacent the neckband portion N (Fig. 5) so that the knot-forming member lies substantially on top of that part of the portion S adjacent the neckband. The long portion L is then brought back under the short portion S (Fig. 6) and thence over and around the knot-forming member as at L₁ in Fig. 7 and upwardly through the loop formed by the now closed neckband N. The portion L is now brought downwardly and passed through the portion L₁ of the tie that lies over the knot-forming member, the portion L, of course, passing between the under surface of the portion L₁, and the outer or front surface of the knot-forming member. The steps in the tying of the necktie in conjunction with the use of the knot-forming member may be the same as those followed in the ordinary four-in-hand procedure.

The completed knot is shown at Fig. 8. The knot-forming member greatly enhances the appearance of the knot and is particularly useful in neckties that are of comparatively lightweight fabric or otherwise lacking sufficient body to provide a neat and substantial knot. The knot-forming member is completely concealed by the finished knot. The gripping action of the hook or tongue 17 is such as to provide for attachment of the knot-forming member to the tie without perforating, tearing or otherwise damaging the tie.

Other desirable characteristics and advantages of the knot-forming member illustrated and described will appear to those skilled in the art. It is not desired that the invention be limited to the precise details set forth.

What is claimed is:

1. A necktie knot form, comprising: a member of substantially uniform thickness having a central body including front and rear surfaces and opposite sides tapering from one end to the other to provide a relatively long upper edge and a relatively short lower edge; a pair of wings joined to and rigid with the sides of the body, one at each side, each inclining rearwardly and laterally outwardly from its proximate side at an obtuse angle to the rear surface of the body and having a terminal side edge positioned in laterally outwardly spaced relation to said proximate side of the body; and a necktie-clasping tongue joined to the upper edge of the body and extending substantially immediately rearwardly thereof and thence directly downwardly alongside of and in closely spaced relation to the rear surface of the body, said tongue lying generally between and being narrower than the lateral spacing of the terminal side edges of the wings and extending a substantial distance toward the lower edge of the body, said tongue further lying forwardly of a plane containing the terminal side edges of the wings, whereby a necktie portion introduced over the terminal side edges of the wings and between the tongue and rear surface of the body will be caused to assume a serpentine formation.

2. A necktie knot form, comprising: a member having a central body including front and rear surfaces, an upper edge, a relatively short lower edge and opposite sides tapering from respective opposite ends of the upper edge to respective opposite ends of the lower edge; a pair of wings respectively rigidly joined to and extending lengthwise of the sides of the body, each wing inclining rearwardly from the front surface of the body and having a terminal side edge positioned rearwardly of the side edge of the body with which it is joined; and a hook element having a root portion rigid with the upper edge of the body and a tongue portion extending downwardly contiguously to the rear surface of the body within the space embraced by said wings, said tongue portion of the hook lying generally between the wings and extending a substantial distance toward the lower edge of the body, and the terminal side edges of the wings being spaced apart more distantly than the width of said hook to provide a tie-receiving space therebetween.
